CLAIM

The ornamental design for a photographic reducing device, as shown and described.

DESCRIPTION

FIG. 1 is a front elevational view of a photographic reducing device, showing my new design;

FIG. 2 is a right side elevational view, the left side being a mirror image thereof;

FIG. 3 is a top plan view thereof;

FIG. 4 is a bottom plan view thereof;

FIG. 5 is a rear elevational view thereof.

*Fig. 1.**Fig. 2.**Fig. 3.**Fig. 5.**Fig. 4.*
